UNITED STATES PATENT OFFICE.

ADOLF DINKLAGE, OF CHEMNITZ, GERMANY.

APPARATUS FOR DRAWING HAIRS AND THE LIKE OUT OF BUNDLES.

No. 830,578.

Specification of Letters Patent.

Patented Sept. 11, 1906.

Application filed March 3, 1904. Serial No. 196,437.

To all whom it may concern:

Be it known that I, ADOLF DINKLAGE, a subject of the German Emperor, residing at Chemnitz, in the Kingdom of Saxony and 5 Empire of Germany, have invented certain new and useful Improvements in Apparatus for Drawing Hairs, Wire, and the Like out of Bundles, of which the following is a specification.

This invention relates to an apparatus for drawing hairs, wire, and the like out of bundles.

The object of the present invention is to provide means for effecting this operation 15 partly or entirely in an automatic way; and the device for this purpose is more particularly intended for use as weft device in hair-weaving looms.

In the annexed drawings my invention is 20 illustrated.

Figures 1 and 2 represent the primary type of my apparatus in perspective. Figs. 3, 4, and 5 show a form of construction of same in elevation, side, and top view, respectively.

If a bundle of hair *a*, Fig. 1, is pressed between the sides of a sufficiently acute angular recess *w*, which I term a "selector," provided with a V-shaped notch, the single hair which reaches the convergence of said selector will be held fast, whereas none of the other hairs will be gripped. If the selector *w* is then moved away from the bundle *a*, Fig. 2, the latter being retained, for instance, by means of a suitable clamping device *c*, the hair *d* at the apex of the selector will be pulled 30 out of the bundle *a*.

To facilitate the insertion of the bundle and to render the gripping of the undermost hair more sure than is the case with a rigid selector, the legs of the selector *w* in the form 40 of construction shown in Figs. 3, 4, 5 are movable. The said legs in this case consist of small plates or shanks *e*, arranged crosswise in the manner of the blades of a pair of scissors or shears, are pivoted at *f*, and controlled or pressed toward each other by plate-springs *g*. This arrangement enables of directly engaging the hair and adjusting the shanks according to the thickness of said hair, which is not the case with a rigid selector and similar devices provided with special means for catching the hair before supplying it to the selector. 45 50

Having now fully described my invention, I declare that what I claim is—

Apparatus for drawing hairs, wire and the like out of bundles comprising a selector provided with a V-shaped notch, consisting of two pivoted spring-controlled shanks arranged crosswise in the manner of a pair of 60 scissors adapted to directly pinch and retain a single hair at their apex, on the removal of the bundle from said selector.

In testimony whereof I affix my signature in presence of two witnesses.

ADOLF DINKLAGE.
